United States Patent

Des. 240,210

Patented June 8, 1976

240,210

COMBINED WATCHFACE AND HANDS THEREFOR

Mark Jeffrey Buckingham, Piscataway, Md.
(Box 18098, Oxon Hill, Md. 20021)

Filed Dec. 18, 1973, Ser. No. 425,726

Term of patent 14 years

Int. Cl. D10—07

U.S. Cl. D10—124

FIG. 2

FIG. 1

FIG. 1 is a front elevational view of a combined watchface and hands therefor showing my new design; the rear being substantially plain and unornamented; and

FIG. 2 is a typical side elevational view thereof.

I claim:

The ornamental design for a combined watchface and hands therefor, as shown and described.
